TUBULAR FOUNDATION GARMENT

Caroline Brown, New York, N. Y.

Application November 8, 1945, Serial No. 627,342

3 Claims. (Cl. 2-30)

1

This invention relates to foundation garments. Broadly, it is an object of my invention to provide a foundation garment which is made from a tubular elastic seamless material. In most foundation garments a great deal of labor is employed in stitching together various pieces of material which may be stretchable or non-stretchable. By using a tubular stretchable material of diagonal weave and cutting the upper and lower portions to receive the brassière and garters respectively, I have found that a great deal of labor is eliminated at the same time providing a serviceable foundation garment which properly supports the parts of the body and is automatically adaptable to the different dimensions of the body. Furthermore, the diagonal weave of the fabric presents a vertical bias stretch which is of advantage in aiding the movements of the body, and giving greater stretch when the wearer is seated.

The greater vertical stretch especially at the thighs gives greater freedom of movement to the legs. My type of foundation garment herein described will permit the wearer to engage in all types of sports while wearing this garment, permitting the muscles of the body to move naturally while supported by the elasticity of the fabric, and without causing the wearer any discomfort or restriction of movement. Since most of the ligaments of the body run at an angle, I have found that my garment with the diagonal weave does not constrict the muscles but supports and persuades the muscles in their movement.

For a fuller understanding of the nature and objects of my invention, reference is had to the following detailed description in connection with the accompanying drawings in which:

Fig. 1 is a front view of a tubular elastic seamless fabric of diagonal weave, showing the upper portion cut out to receive a brassière, the lower portion being cut for receiving garters.

Fig. 2 is a rear view of the tubular fabric shown in Fig. 1.

Fig. 3 is a front view of the tubular fabric shown in Fig. 1, with a non-stretchable panel applied on the material.

Fig. 4 is a rear view of a tubular fabric like that shown in Fig. 1 with a non-stretchable rear panel applied thereto.

Fig. 5 is a front view of a foundation garment made from the tubular fabric shown in Fig. 1 as applied to the figure, showing brassière cups attached to the upper portion, and garters attached to the lower portion.

2

Fig. 6 is a rear view of the foundation garment shown in Fig. 1.

Fig. 7 is a front view of a bathing suit showing brassière cups with elastic material and an elastic crotch member.

Referring to the figures, numeral 10 represents a tubular seamless fabric woven on the diagonal with elastic yarns which may be produced on automatic machines. The tubular material 10 may be of a number of different widths so that each width may be used for persons of several sizes, for example, one width may be used for figures having waist measurements of 24" to 28" inclusive.

Although the tubular material 10 is woven in continuous length, this material is cut to the desired length from the tube in order to provide the main body portion of the foundation garment.

The top of the tube is cut diagonally with the weave of the fabric in the form of two V's as shown at 11 and 12 in order to provide cutouts for the brassière cups 13 and 14 which are stretched at the cutout portions to the elastic tubular material 10. Shoulder straps 15, as is well known in the brassière field, are attached to the upper portion of the brassière cups 13 and 14 and are also attached to the tubular material 10 at the cutout portion of the back of the foundation garment as shown at 16.

30 The lower portion of the tubular material 10 is also cut out with the weave of the material as shown at 17 in order to provide for extensions 18 to which garters 19 are attached. I prefer to provide six garters, two at the front, one at each side and two at the back for fastening to the base.

35 The rear of the tubular material is cut similar to the upper portion, that is with the weave of the material as shown at 20 to provide a large V 40 cut out for the back of the foundation garment as can be readily seen in Fig. 6.

45 When the tubular material 10, with the brassière cups 13 and 14, and the garters 19, and shoulder straps 15 are attached, the entire garment is complete, thus saving a great deal of labor. When the foundation garment is on the figure as shown in Fig. 5, the tubular material 10 automatically adapts itself to the figure, providing support for the muscles both when the figure 50 is at ease and during movements of the body. The arrows in the center of Figs. 5 and 6 indicate that the tubular material 10 stretches in all directions.

55 In the event that it is desired to give greater support at the abdominal region, a non-stretch-

able material 21 in the nature of a panel and having the weave on the straight is applied upon the tubular material 10 so that the abdominal region is supported and the elastic material beneath the panel 21 is prevented from stretching. Of course, any desired shape can be given to the non-stretchable panel 21 depending upon the type of design desired. In the event greater support is desired along the center of the back, a non-stretchable panel 22, set on the straight, may be attached by stitching over the tubular material 10 in order to prevent stretch of the elastic material beneath the panel.

In the event it is desired to cut the back very low so that the wearer can wear certain low cut back dresses and certain types of play and sun suits, the shoulder straps may be dispensed with by providing suitable supports in the brassière cups 13 and 14.

It is within the realm of my invention to adapt the tubular elastic material 10 to a bathing suit by making the brassière cups 23 and 24 with elastic material and with or without shoulder straps as desired by inserting an elastic crotch member 25, shown in Fig. 7. Of course, the lower portion would be cut straight across the horizontal thus saving additional material.

It is obvious that various changes and modifications may be made in the details of construction without departing from the general spirit of the invention.

I claim:

1. A foundation garment of the character described formed of a tubular seamless elastic uniform material completely of diagonal threads and stretchable in all directions, said garment having a pair of brassière cups at the front upper portion, garters at the lower end of said garment for attachment to hose.

2. A foundation garment of the character described formed of a tubular seamless elastic uniform material completely of diagonal threads and stretchable in all directions, said garment having a pair of brassière cups at the front upper portion, garters at the lower end of said garment for attachment to hose and a non-stretchable longitudinal front panel attached by stitching to the central front portion of said garment for supporting the abdominal region of the wearer.

3. A foundation garment of the character described formed of a tubular seamless elastic uniform material completely of diagonal threads and stretchable in all directions, said garment having a pair of brassière cups at the front upper portion, garters at the lower end of said garment for attachment to hose, a non-stretchable longitudinal front panel attached by stitching to the central front portion of said garment for supporting the abdominal region of the wearer, and a non-stretchable longitudinal rear panel attached by stitching to the central rear portion of said garment for supporting the center of the back of the wearer.

CAROLINE BROWN.
